UNITED STATES PATENT OFFICE.

ARNO KAUFMANN, OF PFORZHEIM, GERMANY.

NECKTIE HOLDER.

Application filed March 23, 1926, Serial No. 96,769, and in Germany March 30, 1925.

This invention relates to a neck-tie holder made of bent wire and designed to enable that neck-ties be tied without being placed around the soft or stiff collar and further 5 to stiffen the front part of a soft collar.

The novelty consists in an arrangement in which the ends of the bent wire frame on which the tie is supported form the locking springs of a capsule or detachable member of a collar stud and are held between 10 the front and rear walls of such capsule.

Three embodiments of the invention are shown, by way of example in the accompanying drawing in which:—

15 Fig. 1 shows in elevation a holder, the ends of the wire frame, extending both towards the centre of a capsule like that of a spring button, forming at the same time the springs of said spring-button,

20 Fig. 2 is a plan view of the spring-button capsule,

Fig. 3 shows in elevation the lower portion of the holder the ends of the wire frame, entering from the sides into the capsule of 25 the spring button, form at the same time the holding springs of the spring button.

Fig. 4 is a front view of the spring button capsule.

Fig. 5 is a plan view of the capsule of 30 the button shown in Fig. 4.

Fig. 6 is a central section through the capsule mounted on the collar stud.

Fig. 7 shows in elevation the lower portion of the holder, separate springs for the 35 spring button being arranged in the capsule.

Fig. 8 is a central section through the capsule shown in Fig. 7 mounted on the collar stud.

40 The wire frame 1 which comprises, for instance, a U-shaped transverse arm 2 for holding the neck-tie in the central position, is continued in downward direction by two parallel arms 3, 3 which extend into the

45 capsule composed of a front wall 4 and of a back wall 5. In the capsule they form the holding springs 6, 6 and for the purpose of fixation they are bent to fit into the edge of the back wall 5. The front and back walls 50 4 and 5 have each at the centre an opening

7 through which the head 8 of the collar stud is to be inserted. The openings 7 are however of such dimensions that the abutment plate 9 of the collar stud cannot pass through them. In order to provide a good 55 bearing surface for the holding springs 6, 6 the front wall has a little cavity 10. The thickness of the capsule can thus be very little as it is independent of the length of the head 8 so that the latter projects also 60 through the front wall 4.

Whilst in the first form of construction the arms 3, 3 enter into the capsule through a common hole 11, according to the second form of construction they enter separately 65 through the holes 12, 12.

In the third form of construction the ends 3 of the wires do not serve at the same time as holding springs 6 these springs being formed by separate pieces of wire which are 70 bent accordingly (Fig. 7).

The neck-tie is tied over the wire frame 1 and the wire frame with the neck-tie is then pushed underneath the corner flaps of the collar and mounted on the collar stud. 75 If a person possesses several neck-ties tied on wire frames he can put on the desired neck-tie rapidly and without trouble.

I claim:—

1. A neck-tie holder comprising in combination, a capsule, and a wire frame on which the tie is supported, the ends of said bent wire frame forming the locking springs in said capsule and being held between the 80 front and rear walls of said capsule. 85

2. A neck-tie holder comprising in combination, a capsule composed of a front wall and of a rear wall, said walls having each an aperture for the passage of the holding head of the collar stud so that the thickness of the capsule is rendered independent on the length of the holding head of the stud and may be consequently very short, and a wire frame on which the tie is supported, the ends of said bent wire frame forming the locking springs in said capsule and being held between the front wall and rear wall of said capsule. 90

In testimony whereof I affix my signature.

ARNO KAUFMANN.
